UNITED STATES PATENT OFFICE

2,599,823

WINDOW VENTILATOR

Eugene O. Gillen, Milwaukee, Wis.

Application October 24, 1947, Serial No. 781,857

8 Claims. (Cl. 98—99.2)

1

This invention relates to automatic ventilators to be installed on the inside sill of a window for controlling the temperature and ventilation of the room by regulating the passage of air through the window and ventilator device.

The principal object of the invention is to provide an improved opening and closing ventilator mechanism which is not affected by wind pressure and which operates quietly and efficiently under all conditions.

Another object of the invention is to provide a ventilator cabinet and closure mechanism of new and improved design.

Another object is to provide a ventilator in which the mechanism for closing and opening the ventilator is substantially in balance and is unaffected by forces other than that of the thermostatic control unit.

Another object is to provide a ventilator having a movable member closing the air passage way which will not rattle or flutter.

Another object of the invention is to provide a ventilator of low cost design and inexpensive construction.

Another object is to provide a ventilator of large capacity requiring a relatively smaller, less expensive thermostatic operating device.

Another object is to provide such a closed window ventilator cabinet which will permit the raising and lowering of the window without removal of the ventilator from the window.

These and other objects and advantages of the invention will be more fully disclosed in the following description of a preferred embodiment of the invention as illustrated in the accompanying drawings.

In the drawings:

Figure 1 is a front elevation of the ventilator with parts broken away;

Fig. 2 is an end elevation of the ventilator;

Fig. 3 is a transverse vertical section of the ventilator showing the closure member in half open position;

Fig. 4 is a view similar to Fig. 3 showing the closure member in closed position;

Fig. 5 is a top plan view of the ventilator with the upper grille removed; and

Fig. 6 is a detailed view of the clutch mechanism.

The room ventilator, as shown in the drawings, is adapted to be employed in the ventilation of bedrooms, offices and the like, particularly in winter, where it is desired to prevent cooling of the room below a predetermined temperature. For this purpose the ventilator opening is ther-

2

mostatically controlled to close the same as the temperature of the air within the room approaches a predetermined low temperature.

The ventilator unit comprises a cabinet 1 having extensible panel sections 2 projecting on each side of the cabinet. The cabinet is adapted to be set within the lower part of a window frame 3 on the inside of a room and to cover the opening of the window with the window raised to a certain height. The cabinet is supported within the frame by the panel sections which are adapted to be secured to the opposite sides of the window frame 3.

The air from the outside enters the cabinet 15 through an open side 4 of the cabinet facing the window opening and passes from the cabinet into the room through the grille in the top removable cover of the cabinet. The quantity of air which is allowed to enter the room is controlled by a 20 thermostatic bellows unit 5 disposed within the cabinet at one end thereof and which operates a closure mechanism within the cabinet, as will be described.

The cabinet 1 is generally rectangularly shaped. 25 The open side facing the window opening is straight and the lower, front and top sides are joined in a curve to provide a streamlined appearance.

A single curved member 6 forms the lower and front sides of the cabinet and the curved cover 7 extends over the top of the cabinet.

Two end pieces 8 and 9 corresponding to the shape of the cabinet close each end and are spot welded or otherwise secured along the opposite side edges of member 6 by means of the circumferential flanges 10 around each end piece. Flanges 10 of each end piece extend in the same direction permitting identical members to be employed, thereby saving in tool cost. The end piece 9 having flanges 10 extending outwardly provides the mounting for the thermostatic control 5 as will be described. End piece 9 is joined to member 6 with a marginal portion of flange 10 extending beyond the edge of member 6 to provide 45 means for securing to the cabinet a cover for the thermostatic control, as will also be described.

The cabinet 1 is generally of standard size and the ventilator may be made to fit windows of different widths by providing interchangeable intermediate panel sections of the necessary widths adapted to slide into position by means of the slip joints 11 between the panel sections 2 and the corresponding end pieces 8 and 9.

55 A grille or openwork 12 is provided in the

front side of the cabinet and covered by means of a clear or colored semi-transparent plastic material 13 secured to the inside of the cabinet. The grille provides a more attractive unit and materially reduces the amount of light which is otherwise obstructed and prevented from entering through the window.

A grille 14 in the top cover 7 is provided to allow the air to pass from the cabinet into the room. Cover 7 is secured along the upper edge of front member 6 by means of hinges 15. In closed position the cover rests at either end upon the flanges 10 of end pieces 8 and 9 and when opened upwardly provides access within the cabinet to the closure mechanism or to the window handle for raising or lowering the same.

The closure mechanism comprises a rectangular piece of flexible material or cloth 16 which is secured along one edge to the inside top edge of member 6 by means of a metal strip 17.

A series of metal supporting stays 18 spaced parallel to strip 17 are sewed to cloth 16. An end stay 19 extends along the opposite free edge of the cloth. Rods 20 on each end of the stays 18 and 19 support the closure means and extend downwardly to a shaft 21 disposed near the bottom of the cabinet through end pieces 8 and 9. Collars 22 riding on shaft 21 are secured to the lower ends of each rod 20.

Cloth 16 should be of a size to extend fully between end pieces 8 and 9 and to extend from front member 6 to the window frames. In "open" position the cloth is folded against the inner front side of the cabinet and provides for free passage of air from the window opening through the grille in the top of the cabinet. In "closed" position the cloth is unfolded and carried in an arc around shaft 21 by rods 20 to extend fully to the window to close the top of the cabinet and prevent the passage of air therethrough. Any intermediate position may also be obtained.

The number of stays 18 to be employed may vary according to the size of the cabinet and other factors. Three stays are shown in the drawings.

Opening and closing of the ventilator is effected by rotation of shaft 21. The collars 22 supporting end stay 19 are fixed to shaft 21 to transmit through rods 20 supporting the stay 19 the requisite movement to fold or unfold the cloth 16.

Rotation of shaft 21 in response to temperature changes in the room to open or close the closure mechanism is accomplished by the bellows type thermostatic unit 5 which is mounted on the outer side of end sections 9 above shaft 21 extending outwardly therefrom.

Thermostat 5 is of the thermal expansion type and should be constructed to operate through a selected temperature range with a movement sufficient to rotate shaft 21 and close or open the closure device within any preselected 15 to 20° of the full operating range.

Thermostat 5 is connected to rotate shaft 21 by means of an operating rod 23 connecting the unit 5 and a lever arm 24 on shaft 15. A safety and adjustment clutch 25 drivingly connects lever arm 24 and shaft 21. Upon contraction or expansion of the bellows of unit 5 in response to a change of temperature, unit 5 through rod 23 and lever arm 24 rotates shaft 21 to effect a predetermined corresponding opening or closing of the ventilator unit.

The principle of operation of the thermostati-

cally controlled ventilator device as disclosed herein is substantially the same as that fully described and claimed in my copending application entitled Room Ventilator, Serial No. 679,315, filed June 26, 1946 now Patent No. 2,520,752.

The clutch 25 which is similar to that shown in the above mentioned copending application comprises, in general, a circular plate 26 fixed on shaft 21 and frictionally engaged by the circular base of lever arm 24 under the biasing influence of a dished spring 27.

The lever arm 24 is preferably of organic fiber composition or resin impregnated fiber construction to provide a relatively high coefficient of friction with the metal of disc 26.

The dome-shaped spring 27 has its perimeter engaging the outside of arm 24 and biasing the arm against disc 26. Disc 26 has an ear or lug 28 extending laterally from its outer edge across a recess 29 in the edge of lever arm 24 and into a recess 30 in the circumferential edge of spring 25 so that spring 27 is prevented from turning except with shaft 21 and disc 26. Recess 29 in the circumferential edge of lever arm 24 extends through an arc equal to that desired for maximum turning of shaft 21 at any position of the closure member when the clutch is released.

The spring 25 is held against the plate of lever arm 24 by the collar 31 on the shaft 32. One end of shaft 32 is threaded and extends through a central hole in spring 27 and into a threaded hole in the end of shaft 21. The other end of shaft 32 extends outwardly and has a manual turning knob 33 fitted at the end thereof. By turning knob 33 and shaft 32 the collar 31 is moved to press or release spring 27 and engage or disengage the clutch. By the proper tightening of the collar against the spring the clutch may be adjusted for the required degree of slip tightness. Notches 34 in the face of collar 31 and corresponding elevations 35 in the opposite surface of spring 28 provides a detent locking means to prevent the clutch from slipping out of adjustment.

An end cover 36 partially encloses the thermostatic unit and is mounted to fit the exposed marginal flange 10 of end piece 9 flush with the front and top members 6 and 7. Cover 36 is preferably secured by one or two screws for easy removal and adjustment of the thermostatic unit. Cover 36 is provided with an open grille work to allow the secondary air within the room and circulated by the incoming air to pass upwardly therethrough and ensure the full response of the thermostatic unit to the temperature of the room.

The ventilator cabinet is adapted to be positioned on the inner sill of the window and to remain there at all times. In the summer it may remain open and serves as a shield to control the ventilation of the room and to prevent rain from entering. In the winter it additionally functions to control the temperature of the room as described.

A filter 37 may be provided as shown in the drawings placed along the inner side of the curved cover member 7. The filter may be of any desired composition or type and may be removably secured to the cover 7 by means of clips 38 along opposite sides thereof. The filter is thereby immediately accessible by lifting of cover 7, and is easily removed at any time for replacement or cleaning. Because of its location relative to the window opening the filter is

particularly well protected from rain and snow and will not become wet or freeze. The location of the filter allows the window to be closed without having to remove the same and does not interfere in any way with the window handle.

The arched fabric closure moves to open and close along an arc having a substantial radius and a center in line with the direction of air flow requiring a minimum of mechanical power. Substantially all the thrust of air striking the closure is carried by the shaft 21 in a non-rotational direction and the entire mechanism is protected therefore against sudden surges of air and fluttering.

Since less power is required to operate a closure of this type a smaller or less expensive thermostatic unit or even a bimetallic thermostat may be employed. By reducing the length of the crank arm 24 it is also possible to substantially reduce the operating limits of the thermostat to within 5 or 10 degrees thereby affording a more close control of the air temperature within the room.

The closure cloth is adapted to extend slightly beyond the dimensions of the open side of the cabinet allowing the cabinet to be spaced slightly from the window for clearance while at the same time providing a complete closing of the air opening.

By opening cover 7 and moving the closure device to open position by hand the cabinet is completely unobstructed for access to the window handle to open or close the window as desired without difficulty.

When the closure device is fully opened and the clutch is disengaged the closure cloth will not accidentally "fall" into the window opening and become damaged while lowering the window.

The closure mechanism is free of possible restriction in movement by snow collecting in the base of the ventilator cabinet and will operate regardless of the wind pressures or other weather conditions.

The ventilator may have various embodiments within the scope of the accompanying claims.

I claim:

1. A room ventilator of the class described, comprising a cabinet having an open side to be disposed adjacent a corresponding window opening to receive air from outside, and an open top for the discharge of the air from the cabinet into the room, a flexible expansible closure member to control the entry of air into the room extending the length of the cabinet inside thereof and adapted to be extended selectively across the open top thereof, means securing one edge of said closure member to the front wall of said cabinet and leaving the other edge free to move toward and away from the same, support members for the free edge of said closure member extending downwardly therefrom, a pivotal support for said support members carried by the ends of the cabinet near the bottom thereof, and means to adjust the pivotal position of said support members to hold said closure member in adjusted position.

2. A room ventilator of the class described, comprising a cabinet having an open side to be disposed adjacent a corresponding window opening to receive air from the outside and a fixed opening in the top for the discharge of air from the cabinet into the room, a rectangular expansible closure member secured on one side within said cabinet to one wall thereof, supporting means secured to the opposite side of said mem-

ber and within said cabinet to open and close selectively said member within said cabinet across the open top thereof, said supporting means extending downwardly from said closure member and being pivotally supported near the bottom of said cabinet, and means to secure said supporting means in adjusted pivotal position.

3. A room ventilator of the class described, comprising a cabinet adapted to be disposed adjacent a window opening and having fixed openings for the circulation of air therethrough from outside the window into the room, a flexible folding expansible closure member secured along one edge thereof within said cabinet to one wall of the cabinet, movable supporting means securing the opposite edge of said member and adapted to adjustably control the closure of said openings by the expansion and contraction of said flexible closure member, said supporting means extending downwardly from said closure member and being pivotally supported near the bottom of said cabinet, and means to secure said supporting means in adjusted pivotal position.

4. A room ventilator of the class described, comprising a cabinet adapted to be disposed on a window sill adjacent a window opening and having a front weather shield with closed ends and an open top adapted for the passage of air admitted through the window into the room, a folding closure member adapted to adjustably extend across the opening in said cabinet and having one edge fixed to the front shield of the cabinet, a shaft extending longitudinally of the cabinet near the bottom thereof and extending outwardly through a closed end, a stay member secured to the free edge of said closure member and extending radially from said shaft to effect adjustment of said closure by the rotational position of said shaft, and means at the outer end of said shaft for determining the rotational position of the shaft.

5. A room ventilator of the class described, comprising a cabinet adapted to be disposed on a window sill adjacent a window opening and having a front weather shield with closed ends and an open top adapted for the passage of air admitted through the window into the room, a folding closure member adapted to adjustably extend across the opening in said cabinet and having one edge fixed to the front shield of the cabinet, a shaft extending longitudinally of the cabinet near the bottom thereof and extending outwardly through a closed end, a stay member secured to the free edge of said closure member and extending radially from said shaft to effect adjustment of said closure by the rotational position of said shaft, and a thermostat at the end of said cabinet exposed to room air and connected to said shaft to control the rotational position of the same and the corresponding closure of said ventilator.

6. A room ventilator of the class described, comprising a cabinet having an open side to be disposed adjacent a corresponding window opening to receive air from the outside and an open top for the discharge of the air from the cabinet into the room, a folding closure member to control the entry of air into the room extending the length of the cabinet and adapted to be extended selectively across the open top thereof from the front of the cabinet toward the window, and an open grille member hinged at the front of the cabinet for constituting the top thereof, said grille member being pivotally movable away from the window to provide access to the window sash

when said closure member is folded back away from the window.

7. A room ventilator of the class described, comprising a cabinet having an open side to be disposed adjacent a corresponding window opening to receive air from the outside and an open top for the discharge of the air from the cabinet into the room, a folding closure member to control the entry of air into the room extending the length of the cabinet and adapted to be extended selectively across the open top thereof from the front of the cabinet toward the window, an open grille member hinged at the front of the cabinet for constituting the top thereof, said grille member being pivotally movable away from the window to provide access to the window sash when said closure member is folded back away from the window, and a filter removably secured inside said cover member and extending across the grille thereof in the path of ventilating air. 10

8. In a room ventilator having a housing adapted to be disposed in a window between the sash and sill thereof with a fixed opening for the passage of air therethrough, a bellows closure for said opening disposed in said housing and having one edge of the bellows secured along a corresponding edge of the opening, an adjustable support for the free edge of said bellows movable to control the closure of the opening by the expansion and contraction of the bellows, said support 15

5

extending from said closure substantially normal to the plane of said opening, and means to pivot the end of said support at a substantial distance from said closure for adjustment of said closure.
